(57) **CLAIM**

The ornamental design for a microscope, as shown and described.

DESCRIPTION

This application is related to co-pending application Ser. No. 29/311,060, entitled "Microscope".

FIG. 1 is a front, right perspective view of a microscope showing my new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

The broken lines form no part of the claimed design.
